UNITED STATES PATENT OFFICE.

WILLIAM S. ORTH, OF DUNKIRK, OHIO.

SHINGLE.

1,077,095.

Specification of Letters Patent. Patented Oct. 28, 1913.

Application filed April 3, 1913. Serial No. 759,637.

To all whom it may concern:

Be it known that I, WILLIAM S. ORTH, a citizen of the United States, and a resident of Dunkirk, in the county of Hardin and State of Ohio, have invented a new and Improved Shingle, of which the following is a full, clear, and exact description.

This invention relates to shingles and has reference more particularly to a shingle provided along one of its edges with an extension or off-set serving as a gage or guide in applying the shingle.

The object of my invention is to provide a simple, strong and durable shingle which may be fashioned from any suitable composition or other material adapted for the purpose which can be used for roofing, siding, decorating and other purposes by means of which a water and weatherproof cover can be applied to roofs or walls, which is so constructed that the shingles can be accurately spaced and located when being applied, by means of which the use of striking lines or straight edges is obviated as the shingle constitutes a gage in itself, and which minimizes the expenditure of time and labor in applying the shingles.

The invention consists in the construction and combination of parts to be more fully described hereinafter and particularly set forth in the claims.

Reference is to be had to the accompanying drawings forming a part of this specification in which similar characters of reference indicate corresponding parts in all of the views and in which,

Figure 1 is a perspective view of an embodiment of my invention; Fig. 2 is a plain view showing a number of the shingles laid; Fig. 3 is a similar view showing the shingles disposed in a different arrangement; Fig. 4 is a plain view of a modified form of my invention; Fig. 5 is a plain view of a further modified form of shingle; and Fig. 6 is a similar view of another modified form of the invention.

Before proceeding to more detailed explanation of my invention it should be clearly understood that while the shingle is preferably of the prepared or composition kind it can also be of other material, for example wood. The invention itself may be embodied in different forms, and may be plain or ornamental.

Referring more particularly to the drawings Figs. 1, 2 and 3, I provide a shingle

having a body 10 of substantially rectangular form and of greater length than width. The shingle is in effect of oblong shape having parallel transverse edges 11 and parallel longitudinal edges 12. The shingle is of suitable thickness, and if it is so desired may have the corners slightly rounded. Disposed along one of the longitudinal edges 12 the shingle has an extension 13 and along one of the transverse edges 11 a similar extension 14. These extensions join at one corner of the shingle, and each extends along its edge of the shingle for a distance slightly exceeding one half the length of that edge.

In Fig. 2, I have shown a number of the shingles laid and spaced apart in each instance the width of an edge extension. These extensions, it will be readily understood, act as guides or gages in laying the shingles, permitting them to be accurately lined and disposed with reference to each other. In Fig. 3, I have also shown a number of shingles laid, but disposed in different arrangement, that is, with their lengths horizontal. This arrangement is distinguished from that shown in Fig. 2 in which lengths of the shingle are disposed vertically.

In Fig. 4 is shown a modified form of shingle in which the body 15 is of such dimension that it in effect constitutes three shingles of ordinary size. It has at one edge an extension 16 corresponding to the extension 13 of the previously described form of shingle. In addition it is provided with two slots 17 spaced equi-distance from the ends of the shingle. These slots extend inwardly from the lower edge as far as the extension 16, and correspond in width, to that of the extension itself and like the same serve as guides or gages in the laying of the shingles. Furthermore, they accord the shingle the appearance of three separate shingles.

In Fig. 5 is illustrated a further modified form of the shingle which comprises a body 18 equivalent in size to one and a half shingles of the previously described form. It has along one of its end edges an extension 19 corresponding to the extension 13 of the ordinary shingle. It likewise has at its lower edge a slot 20 corresponding to one of the slots 17 of the shingle shown in Fig. 4 and serving a like purpose.

In Fig. 6 is shown a shingle 21 having

2
extensions 22 and 23 like corresponding parts 13 and 14 of the shingle 10. Its lower portion 24, however, is provided at the corners with arcuate edges 25, to render this shingle of ornamental form. Other than this its proportions are similar to those of the preferred device.

Having thus described my invention what I claim as new and desire to secure by Letters Patent is:—

1. A shingle provided along two of its adjacent edges with extensions adapted to constitute guides or gages.

2. A shingle of oblong form having along two of its adjacent edges extensions, constituting guides or gages, and each extending along its edge of the shingle for a distance somewhat exceeding one half the length of that edge.

In testimony whereof I have signed my name to this specification in the presence of two subscribing witnesses.

WILLIAM S. ORTH.
